UNITED STATES PATENT OFFICE.

ELMORE STEWART, OF LOS ANGELES, CALIFORNIA.

OIL-BURNER.

SPECIFICATION forming part of Letters Patent No. 709,370, dated September 16, 1902

Application filed May 6, 1901. Serial No. 58,953. (No model.)

To all whom it may concern:

Be it known that I, ELMORE STEWART, a citizen of the United States, and a resident of Los Angeles, in the county of Los Angeles and State of California, have invented a new and Improved Oil-Burner, of which the following is a full, clear, and exact description.

This invention relates to an improvement in a burner for crude petroleum or other of the distillates or products therefrom; and the object is to provide a burner in connection with a cooking or heating stove, hot-air furnace, steam and water heating system, steam-boiler, and hotel-range of simple construction and so arranged that a very strong and hot flame will be maintained.

I will describe an oil-burner embodying my invention and then point out the novel features in the appended claim.

Reference is to be had to the accompanying drawings, forming a part of this specification, in which similar characters of reference indicate corresponding parts in all the figures.

Figure 1 is a perspective view of a stove having a burner embodying my invention. Fig. 2 is a sectional elevation of the same, and Fig. 3 is a plan view of the burner-body.

Referring to the drawings, 1 designates a cooking or heating stove having a stove-cover 2 in its top, the said stove-cover having a central opening to admit a downdraft-tube 3. This downdraft-tube 3 is shown as tapered, the lower end within the stove being smaller than the upper end. The upper end is provided with an annular flange 4 to rest upon the stove-cover 2, as clearly shown in the drawings. Below the downdraft-tube is a burner-body 5. This burner-body is made in the form of a cup, and the bottom 6 thereof

is made conical, and at the apex thereof is a depression or cup 7. Over this depression or cup leads a supply-pipe 10 for conveying the heating medium, which is furnished from any suitable source—as here shown from a reservoir 9.

In operation the oil will drop or run from the supply-pipe through the downdraft-tube with such force that when it strikes the cup 7 it is atomized in the burner 5, where it will be ignited, sending up a very strong flame, for all of the other drafts or openings in the stove are closed and all air for supporting combustion will be necessarily drawn downward through the tube 3, and the products of combustion will pass out through an uptake 55 or pipe 11.

Having thus described my invention, I claim as new and desire to secure by Letters Patent—

The combination with a stove or heater, of a burner movable from place to place in the stove or heater, the said burner consisting of a cup-shaped body having a conical bottom closure provided with a depression at its apex, the said apex being below the open top of the body, an oil-supply tube arranged above the stove or heater and in line with said depression, and a downdraft-tube supported independently of and wholly above the burner, substantially as specified.

In testimony whereof I have signed my name to this specification in the presence of two subscribing witnesses.

ELMORE STEWART.
